UNITED STATES PATENT OFFICE.

ELMER C. DAVIS, OF FAIRFIELD, IOWA.

BREAST-COLLAR HARNESS.

1,331,488.

Specification of Letters Patent.

Patented Feb. 24, 1920.

Application filed June 25, 1917. Serial No. 176,746.

To all whom it may concern:

Be it known that I, ELMER C. DAVIS, a citizen of the United States, residing at Fairfield, in the county of Jefferson and 5 State of Iowa, have invented certain new and useful Improvements in Breast-Collar Harness, of which the following is a specification.

This invention relates to improvements in 10 breast-collar harness, and among its objects are to provide such harness in which the breast strap is made in two parts detachably connected together; further to provide specifically formed overlapping plates secured to 15 the two parts of the breast harness, whereby these parts may be quickly and readily connected or disconnected as desired; further to provide a separate removable plate to be inserted between the overlapping plates when 20 desired, whereby the breast harness may be quickly made available for use as double harness in hitching to a double rig; to provide such breast-harness that will make it easier to harness or unharness; that will permit 25 of using shorter lengths of leather in making breast harness; that will add to the attractiveness of the harness; that will permit of the renewal of parts without buying the entire breast harness new; and to provide 30 such combination, construction and arrangement of parts that will result in a more simple, efficacious and economical breast harness than heretofore known.

Other objects and advantages will appear 35 as the following description proceeds, and while I have illustrated in the accompanying drawings a preferred embodiment of my invention, I desire it to be understood that the same is susceptible of modification and 40 change without departing from the spirit of my invention, except as limited by the appended claims.

In the drawings:

Figure 1 is a perspective view of my improved breast-collar harness, showing the parts in assembled relation.

Fig. 2 is an enlarged side elevation of the attaching device in a slightly separated position.

Fig. 3 is a longitudinal cross sectional view through Fig. 2.

Fig. 4 is an enlarged longitudinal cross sectional view through the front portion of Fig. 1.

Fig. 5 is a side elevation, to smaller scale

than Figs. 2, 3 and 4, of the plate used when hitching to a double rig.

Fig. 6 is a vertical transverse sectional view through Fig. 5.

Referring to the drawings:

In Fig. 1 my improved breast-collar harness, designated generally by A, is composed of the two parts 1 and 2, to which is secured the usual shoulder strap 3. Secured by rivets 4 or other suitable means to the end of the part 1 is the flat plate 5, which is positioned in the cut away portion 6 of part 1 as shown in Fig. 3. Struck up from the body portion of the plate 5 are the projections 7 and 8, in which projections are formed the slots 9 and 10, said projections and slots being in longitudinal alinement. Secured to the end of the part 2 by rivets 11 or other suitable means is the flat plate 12, in which are provided the transverse slots 13 and 14, which slots are spaced apart a distance equal to that between the projections 7 and 8. Also secured to the plate 12 upon the end opposite to the slots 13 and 14 by means of the rivet 15 or other suitable means is the flexible tongue 16 formed of leather or other suitable material.

As will be apparent from this construction, when it is desired to secure together the parts 1 and 2, the plates 5 and 12 are brought into overlapping relation with the slots 13 and 14, registering with the projections 7 and 8, respectively, after which these projections may be pushed through said slots and the overlapping plates brought into engagement with each other, and the flexible tongue 16 then inserted through the slots 9 and 10, which securely fastens these overlapping plates together.

This gives a construction in which the parts 1 and 2 of the breast harness when desired may be readily separated by merely withdrawing the tongue 16 from the slots 9 and 10 and removing the plate 12 from engagement with the plate 5; also by the reverse operation these parts may be quickly secured together.

As shown in Figs. 5 and 6, I have also provided a flat plate 17, having two parallel vertical slots 18 and 19 in its upper portion, and a horizontal slot 20 near its lower portion. The purpose of this plate 17 is to make my improved breast harness readily adaptable for use as double harness in hitching to a double rig. In order to do this, it is only

necessary, when the plates are secured in overlapping relation, to remove the flexible tongue 16 from its position through the perforated projections 7 and 8, remove the plate 12 from engagement with the plate 5, then place the plate 17 upon the plate 5 with projections 7 and 8 extending through the slots 18 and 19, respectively, then replacing the plate 12, with the projections 7 and 8 extending through the slots 13 and 14, and finally inserting the tongue 16 through the slots 9 and 10. The yoke strap of the double harness may then be inserted through the slot 20, and the double hitch proceeded with in the usual manner. If it is desired to use my breast harness when driving single, the plate 17 may be removed from between the overlapping plates 5 and 12, (unless it is desired to leave this plate in such position,) after which my improved device may be used the same as though the plate 17 had not been provided.

It will be noted that as a result of inserting the plate 5 in the cut away portion 6, when the plates 5 and 12 are placed in overlapping engagement, the inner faces of the parts 1 and 2 will present a continuous surface, thus eliminating any undesirable projections at this point to interfere with or rub sores on the horse's breast.

It will be seen from the foregoing that I have provided a device which is capable of use in either single or double harness, and in which the breast harness may be quickly and conveniently removed without passing the strap 3 over the horse's head. As before stated, the plate 17 is only necessary when hitching double, and when hitching single it may be entirely omitted if desired, thus producing a very simple device with all the advantages as hereinbefore set forth.

Having now described my invention, I claim:

1. In breast-collar harness, a breast strap formed in two parts, two plates, one plate secured to each of said parts, said plates

being adapted to overlap, means on said plates to detachably secure them together, a third plate adapted to be rigidly and detachably secured between said two first mentioned plates, and means on said third plate to receive the neck yoke strap of double harness.

2. In breast-collar harness, a breast strap formed in two parts, two plates, one plate secured to each of said parts, one of said plates having a plurality of perforated longitudinally aligned projections struck up from the body thereof, the other of said plates having a plurality of transverse slots adapted to fit over said projections when brought into registry therewith, a third plate also having a plurality of slots to fit over said projections when said third plate is placed between said two first mentioned plates, and a flexible tongue secured to said second mentioned plate and adapted to be inserted through the perforated lugs, and a horizontal slot in said third plate to receive a neck yoke strap.

3. In breast-collar harness, a breast strap formed in two parts, a plate secured to the end of each of said parts, said plates being adapted to overlap each other and one of them having a perforated projection extending from its outer face and the other an opening through which said projection is adapted to pass, a third plate also having an opening therein to fit over said projection when placed between said two first mentioned plates, and means on one of said plates to pass through the perforation in said projection to hold said three plates in assembled relation, and means on said third plate to receive a neck yoke strap.

In witness whereof, I hereunto subscribe my name to this specification in the presence of two witnesses.

ELMER C. DAVIS.
